UNITED STATES PATENT OFFICE.

JOSEPH C. LUCAS, OF BLANDINSVILLE, ILLINOIS.

PROTECTING SHIELD FOR BANK AND OTHER WINDOWS.

Application filed April 4, 1925. Serial No. 20,751.

To all whom it may concern:

Be it known that I, JOSEPH C. LUCAS, a citizen of the United States, residing at Blandinsville, in the county of McDonough 5 and State of Illinois, have invented certain new and useful Improvements in Protecting Shields for Bank and Other Windows, of which the following is a specification, reference being had to the accompanying drawings.

This invention relates to devices for protecting cashiers and other officials at the windows of banks, and particularly to certain improvements upon the device for this purpose illustrated, described and claimed in my pending application for patent, Serial #752,493, filed on the 26th day of November, 1924.

In my prior application, I showed a shield 20 which was supported at the window opening of a teller's or cashier's cage and which was normally held up by a latch. This latch was adapted to be released by a solenoid to permit the window to fall, the solenoid being energized by the pressure of a button or like circuit-closing device.

One of the objects of the present improvement is to provide means whereby the descent of the shield, if it should accidentally 30 occur, will not injure anyone whose hand happens to be on the ledge beneath this shield when the shield descends.

A further object is to provide a device of this nature comprising a safety door or section hinged to the lower end of the main section of the shield and normally supported in a raised position, which door is so constructed that when the shield descends it is automatically released and automatically 40 swings downward through the action of a spring closing the opening which would otherwise be left between the lower end of the shield and the ledge and preventing the robber from shooting through the opening which would otherwise be left.

A still further object is to provide for stopping the descent of the window, which means will actuate and release the safety door and cause it to automatically close, and 50 to provide means for latching the safety door in its automatically closed position.

Another object is to provide means for automatically latching the shield in its lowered position, and provide means whereby 55 this latch may be readily released.

Still another object is to provide improved means for actuating the signal when the shield has fallen completely down.

Other objects will appear in the course of the following description.

My invention is illustrated in the accompanying drawings, wherein:

Figure 1 is an elevation of the face of a partition wall, to the windows of which my invention is applied;

Figure 2 is an inside view of the partition shown in Figure 1 and showing my improved shields lowered;

Figure 3 is a perspective detail view of the hinge upon which the safety door is 70 mounted;

Figure 4 is a vertical sectional view on the line 4—4 of Figure 2 showing the shield raised;

Figure 5 is a section on the line 5—5 of 75 Figure 2 showing the shield lowered;

Figure 6 is a section on the line 6—6 of Figure 4;

Figure 7 is a fragmentary vertical section 80 through the frame of the door showing the circuit-closing signal device;

Figure 8 is a fragmentary vertical sectional view through the frame of the opening showing the shield closed and latched;

Figure 9 is a like view to Figure 8 but 85 showing the position of the latch when the shield is raised;

Figure 10 is a diagrammatic illustration of the manner in which the shield may be 90 operated by a button and showing the signalling circuit.

Referring to the drawings, 6 designates the opening in front of a teller's or cashier's cage, it being understood, however, that the device is applicable to any opening and I 95 do not wish to be limited to this use of the device, which is purely illustrative. This opening is normally open but may be closed by a sliding shield 7, this shield being mounted in guides formed as part of the framework 8 of the door. This frame may consist of steel or other strips of structural iron work formed to provide a groove 9 within which the margins of the shield operate.

Mounted upon the frame 8 is a cross bar 10 carrying upon it the ears 11 between which is mounted the pivoted latch 12. The inner end of this latch is formed to engage the keeper 13 upon the sliding shield 7, 110

The outer end of the latch is engaged by the core 14 of a solenoid 15, this solenoid being shown as suspended from a bracket 16 by means of an adjusting screw 17 and 5 as being connected in circuit with a source of current and with a push button 18. When the push button is depressed, the circuit is closed, the solenoid is energized, the core is drawn upward, and the latch 16 is 10 released from its engagement with the shield and the shield, therefore, falls of its own weight.

So far I have described practically what is illustrated in my prior application for 15 patent, but one of my improvements consists in applying to the lower end of the shield 7 a safety door or shield section, designated 19. This at its ends is mounted upon hinge members 20. These hinge members 20 engage on the inside faces of ears 21 which are attached to the shield 7. These hinge members support the safety door or section 19, which is preferably about four inches wide and, of course, has a length 25 equal to the width of the shield. This door is normally held open by a light spring 22 which is attached to the shield and engages over the margin of the door and the door may be urged to a closed position either by 30 gravity or by a spring.

Mounted upon each hinge member 20 is a spring 23, the free end of which bears resiliently against the rounded or circular face 24 of the corresponding ear 21. This circular 35 face at one point is formed with an indentation or notch 25 and when the door swings to its closed position, this spring riding over the edge face of the ear snaps into this notch and thereafter prevents the inward movement or opening movement of the door and 40 locks the safety door or section in its closed position until this spring is manually pulled outward and the locking device released. Inasmuch as this spring and the 45 ears 21 are disposed upon the inside face of the safety door, it is obvious that a robber will not have access to this locking device, which will lock the safety door downward. At the same time, in case a customer 50 or an official of the bank should happen to have his hand out upon the ledge 26 toward which the shield 11 moves, then if by accident the shield should drop there would be ample space between the lower edge of the 55 shield and the sill or ledge to prevent any possible contact between the lower edge of the shield and the customer's hands and the safety door would simply swing downward from the rear, giving a rap to the 60 hands but otherwise not injuring them in any way.

The shield 7 is held from descent to the ledge or sill 26 by means of steel stops 27 disposed in the grooves 13 and at the lower 65 ends of said grooves. Each piece of steel

preferably carries at its upper end a copper cap 28. When the shield falls it strikes this copper cap and the shield stops, while the safety door or section 19 is jarred loose from its engagement with the spring 21 and 70 swings downward, as in the manner heretofore stated. When the shield drops to its closing position it is locked by means of a spring latch 29 mounted upon the inside one of the guide strips 8 and resiliently 75 urged inward, the shield being provided upon its margin with a notch 30 into which this latch is adapted to spring when the shield drops and reaches its fully lowered position. The face of the corresponding strip 8 is apertured for the passage of a knob or handle 31 whereby this spring may be released to permit the shield to be lifted by means of the handle 32. Preferably there is a pad, designated 33, on the bottom of the safety door, which pad is made of any substance which is pliable or elastic so as to prevent any chance of the device injuring a person on closing.

A bell ringing contact 35 is placed upon the inside face of one of the strips 8 operating within the groove 9, this contact being a spring urged away from a coacting contact member 36. These contact members are connected in circuit with a bell 37 and a source of energy 38, as illustrated diagrammatically in Figure 10, and when the door descends this spring is forced inward, engaging the contact 36 and closing the circuit between the bell and the source of energy, thus causing the bell to ring and give an alarm.

As illustrated in my prior application, this shield is particularly designed to be used in connection with banks, though it may be used in any other situation in which such a shield is desirable. This shield is adapted to fall upon the sill 26 which forms the usual shelf projecting into the cage and out therefrom. This window may be located within the usual partition or wall A, which wall is preferably bullet-proof. The push button 22 whereby a circuit is closed through the solenoid may be located at any desired point but preferably, of course, will be placed so that it cannot be accidentally operated. Preferably there will be a number of push buttons, each connected in circuit with all of the solenoids and the source of energy, so that if any official of the bank is attacked or believes himself in danger of being attacked by a robber he or any other officer may press the nearest push button and cause the descent of all of the shields.

The shield, while being made of metal, may be made of any bullet-proof material and of any desired dimensions and I do not wish to be limited to the particular manner of holding this shield in its raised position or for causing the descent of the shield or its shifting into its proper place.

I claim:—

1. The combination with a wall opening, of a vertically slideable bullet-proof shield adapted to be shifted to a position to close 5 said opening and urged to said position, the advance end of the shield being formed with a hinged section, and means normally holding the hinged section open but releasing the hinged section to permit it to close when the 10 shield has reached its closed position.

2. The combination with a wall opening, of a bullet-proof shield normally supported above said wall opening but adapted, when released, to fall across said wall opening to 15 close the same, means limiting the downward movement of the shield to a position where the lower edge of the shield is in spaced relation to the lower edge of the wall opening, a shield section hingedly mounted 20 upon the shield and urged into a position of alignment with the shield, and means holding said section in an open position but automatically releasing said section when the shield reaches its lowest position.

25 3. The combination with a wall having an opening, of a shield shiftable across said opening, means urging the shield to a position to close the opening, means limiting the movement of the shield to a position 30 where its advance edge is spaced from the adjacent edge of the wall opening, a shield section hinged to the main body of the shield and normally urged into a position of alignment therewith, and means holding said 35 shield section out of said position but releasing the shield section when the shield has reached its fully lowered position.

4. The combination with a wall having an opening, of a shield adapted to close 40 said opening, guides on either side of the opening within which the shield slides, stops disposed in said guides above the lower edge of the opening to thereby limit the downward movement of the shield, releasable means holding the shield raised, a 45 shield section hingedly connected to the lower edge of the shield and urged to a position of alignment therewith, and means holding said shield section normally open 50 and releasing the shield section when the shield has contacted with said stops.

5. The combination with a wall having an opening, of a shield adapted to close 55 said opening, vertical guides disposed on each side of said opening within which the shield operates, releasable means holding said shield raised, stops behind said guides limiting the downward movement of the shield to a point where the bottom of the 60 shield is in spaced relation to the bottom of the opening, a shield section hinged to the lower margin of the shield and adapted

to close the space between the lower edge of the shield and the lower edge of the door opening when the shield is lowered, and 65 means normally holding said section raised but releasing said section to permit it to close said remainder of the opening when the shield has struck said stops, said means including a member having a notch, and a 70 spring latch adapted to engage in said notch when the section is turned out of alignment with the shield.

6. The combination with a wall having an opening, of a shield adapted to close said 75 opening and urged to its closed positions, stops limiting the movement of the shield to its closed position to a point where the advance edge of the shield is in spaced relation to the confronting edge of the opening, a shield section hingedly connected to the advance edge of the shield and urged to a position in alignment with the shield, and a spring mounted upon the shield and 80 engaging over the edge of the section and normally holding the section open but releasable by the shock of the shield striking said stops.

7. The combination with a wall having an opening, of a shield adapted to close said 85 opening and urged to its closed position, stops limiting the movement of the shield to its closed position to a point where the advance edge of the shield is in spaced relation to the confronting edge of the opening, a shield section hingedly connected to the advance edge of the shield and urged to a position in alignment with the shield, a 90 spring mounted upon the shield and engaging over the edge of the section and normally holding the section open but releasable by the shock of the shield striking said stops, and means for locking the section in its closed position.

8. The combination with a wall having an opening, of a shield adapted to close said 95 opening, slidably supported means holding said shield raised, the shield being urged downward to a closed position, stops limiting the downward movement of the shield 100 to a point where the lower edge of the shield is in spaced relation to the lower wall of the opening, a safety section hinged to the shield upon the inside face thereof and urged to a position in alignment with the shield, means for holding the safety section 105 raised but permitting the safety section to fall to its lowered position when the shield has struck said stops, and a yielding pad 110 carried by the lower edge of the shield.

In testimony whereof I hereunto affix my signature,

JOSEPH C. LUCAS.
